FILLING OF CODE SLOTS OR NOTCHES
IN EMBOSSED PRINTING PLATES OR
STENCILS

Alfred Vang, New York, N. Y.

Application November 9, 1944, Serial No. 562,694

7 Claims. (Cl. 219—8)

1

This invention relates to new and useful improvements in the filling of code slots or notches in embossed printing plates or stencils.

In the mailing of large numbers of magazines to subscribers, it is customary to address each item of mail by automatic printing machines, which are operated so that a succession of address printing plates is fed into the machine and the name and address, as well as other symbols designating certain information in regard to a subscriber are automatically printed from a plate. Such plates frequently are notched in accordance with the expiry date of the addressee's subscription, so that when the wrapper for the expiring issue is addressed, sensors or feelers cooperate with the code notches to cause a withdrawal of the plate from the active lots, or to otherwise signal that the subscription of the addressee is expiring.

Heretofore it has been customary to discard the out-of-date plate and provide a completely new plate when the subscription is renewed. Such procedure necessitates the striking of a new plate which entails the copying of the name and address and other informative symbols, etc.

Errors of copying frequently occur due to difficulty in reading the plate, and other sources of human error. In one instance where the number of active subscribers is over 5,000,000, the cost of each error is estimated at over one dollar.

My invention has for its object the filling of the code notches, so that the plate may be retained in use by the cutting of appropriate new notches, and thus avoid the waste of strategic metal and avoid errors in printing. The filling of the notches must be carried out with great accuracy. If the filling is incomplete the sensor or feeler may cause the plate to be rejected prematurely. On the other hand, burrs may cause jamming of the automatic printer and other handling mechanism.

Another object is to provide a device for automatic application of alloy material to enable the filling of the code notch by soldering or eutectic welding.

Still another object is to provide a device which may be operated in conjunction with known automatic printing means hitherto in use.

The invention comprises means for holding the address plates and means for applying the alloy to the marginal portions of the notch, so that when the alloy is melted the notch will be filled.

In the accompanying drawing showing, by way

of example, three of many possible embodiments of the invention.

Figure 1 is a plan view showing the printing plate and code notch therein.

5 Figure 2 is an end elevation showing the plate.

Figure 3 is a plan view showing one form of the notch filling device, and portions of a known printing machine.

Figure 4 is a side elevation showing the device 10 of Figure 3.

Figure 5 is a fragmental enlarged sectional view showing details of Figure 4.

15 Figures 6 to 9, inclusive, are partially diagrammatic representations showing operational stages of another form of the invention.

Figure 10 is a horizontal sectional view, partly in elevation, showing the invention of Figures 6 to 9, the section being taken substantially on the line 10—10 of Figure 6, looking in the direction 20 of the arrows of said line.

Figure 11 is a side elevation showing another form of the invention;

Figure 12 is a plan view of the invention shown in Figure 11; and

25 Figure 13 is an enlarged fragmental section, showing details of Figure 11, the section being taken along the line 13—13 of Figure 12.

Referring more particularly to the drawings, my invention for filling code notches 10 in an 30 address plate 11 is shown in connection with a printing machine (shown in part) having a channel guide or track 14 for the address plates and having a printer 15 above said track. The printing machine is provided with known means (not shown) for intermittently passing a succession of address plates longitudinally along said track and with means (not shown) for depressing the printer against each of said plates when the plate reaches a definite position under the printer.

40 My novel notch filling device, generally designated as 16, is mounted adjacent said track 14 and is adapted to be set at various positions longitudinal of the track and comprises a flat horizontal bed plate 18 in fixed relation to and near

45 the track and provided with a slot 19 parallel to the track. A base 20 disposed on the bed plate is adjustably secured thereto by bolts 21 passing through the slot 19 and is provided with a standard 22 rising from the base. A tube 24 projects

50 horizontally from the lower part of the standard, the outer end portion being provided with a vertical diametric hole 25 immediately above the code notch 10 to be filled. The bore 26 of the tube extends through the standard and is provided with a T inlet means 28 for introducing wire

solder or a welding alloy rod 29 into the bore at right angles thereto near the vertical hole 25, whereby a plunger rod 30 adapted to reciprocate in the bore of the tube 24 may shear off and force a bit of solder to the diametric hole.

The outer upper part of the standard 22 is provided with an outwardly open yoke 31 between the arms of which is pivotally mounted an L lever 32, while an arm 34 projects inwardly from the upper part of the standard and over the tube 24. The standard 22 is provided with a large vertical bore 35 open at the top and having a guide rod 36 slidably received therein, so that an actuating bar 38 secured fast or rigid on the upper end of the guide rod 36 may be vertically reciprocated in a horizontal position. An electrode holder member 39 is vertically mounted on the inner end of the bar and slidably passes vertically through a hole 40 in the arm, so that the welding electrode 41 at the lower end of the member 39 may force the solder or alloy downwardly into the notch 10.

The quantity of the solder fed to electrode hole 25 may be determined by an adjusting screw 42 threaded through the outer end portion of the bar 38 and projecting downwardly and provided with a hinged foot 43, adapted to engage the lever 32 latchwise, as will be described in the mode of operation. A spring 44 about the guide rod 36 compressed between the bar 38 and standard 22, retracts the electrode.

In operation a succession of plates 11 is fed intermittently along the printing machine track 14, so that code notch 10 corresponding to say, August, always stops at a particular point on the track. This manner of feeding may be accomplished by the hitherto known printing machine. The novel filling device 16 is then slid along the bed plate 18, so that the electrode hole 25 will be over the point where the notch, corresponding to August, on each successive plate will stop and there be held in position by bolt 21. As the bar 38 is depressed, the screw 42 and electrode member 39 are forced downwardly. The screw and foot 43, acting through the lever 32, first cause the rod 30 to move inwardly and shear off a piece of solder and deposit it at the hole 25, where it is held by a tight fit or is allowed to fall upon the code notch. As soon as the rod 30 has moved far enough inwardly to deposit the solder, the foot 43 slips off the end of the outer arm 46 of the lever, so that the rod 30 does not enter the hole 25, but is immediately retracted by spring 47 under tension between the head 48 of the rod 30.

Further depression of the bar 38, therefore does not cause further movement of the rod 30, but continues to lower the electrode member 39 and electrode 41; the latter, if necessary, expelling the bit of solder downwardly from the hole. As the solder is squeezed between the plate 11 and the electrode 41, a source of current (8, 9) is applied to the plate and electrode, so that the solder is melted and forced into the notch. By proper selection of the size of the solder wire or welding rod, and the bore 26 of the tube, the amount of solder or alloy exactly needed for filling the standard sized code notch may be determined. When each plate reaches a definite point, the printer 15 makes a downward stroke and by means of a suitable motion transmitter, such as bar 45, the bar 38 is depressed.

On upward movement of the bar 38, the foot 43 swings outwardly on hinge 43', so that the foot is once more above the arm 32 of the L lever.

In another form of the invention all feeding of the alloy and movement of the electrode may be

effected by solenoids controlled by a timer 49. Such a form, as shown in Figure 6, comprises a track 14', provided with a marginal recess 50. As plates 11 are fed longitudinally along the track, the code notch 10 is brought substantially under a downwardly fed wire or rod of alloy material 29. The wire is fed by suitable means, such as by rollers or wheels 51, one of which is intermittently rotated by a ratchet and pawl mechanism 52, actuated by a solenoid 54 and spring 55. The wire usually carries a ball or lobe 55' of varying size and shape at its lower end, as a result of the proceeding cycle of operations and consequently the ball is not suitable for supplying a controlled amount of alloy to the notch. The wire is therefore fed downwardly and guided by an inwardly yieldable tube 59, so as to be practically outside the notch, so that the lobe or ball may pass below the plate, as shown in Figure 7 and the wire itself be partially in or opposite the notch.

A horizontally reciprocatory electrode 56 is actuated by a solenoid 57; said electrode is provided with a horizontal recess 58 adapted to receive therein the marginal portion 13 of the plate 11. After the wire or rod 29 is positioned, as described above and shown in Figure 7, the excess length or lobe 55' of the wire 29, which projects below the plate 11, is then smoothly cut off by means of a blade-like end portion 60 of the electrode 56, which latter then forces the wire 29 tightly into the notch 10, as shown in Figure 8.

Finally after the alloy is well placed on the notch, a current is applied (Figure 8a) to the electrode and plate to melt the alloy, whereupon the molten alloy is forced into the notch by a somewhat molding action of the electrode. Upon melting of the alloy, the wire stock is severed from the material in the notch.

All movements and the application of the welding current are timed by the timer 49, connected to a suitable source of current L1, L2.

When the notch has been filled by alloy, as in Figure 8a, the guide tube 59 is allowed to swing outwardly and a jet of cooling air is applied to the filled notch by means of a pipe 62, so that the alloy is quickly solidified, and another plate is moved into position to be acted on in a similar manner.

When the number of plates to be renovated 50 is large (one publisher must be able to meet a peak load of more than a hundred thousand a day), several notch-filers may be located at one track and the plates advanced therewith in a series equal to the number of notch-filers. In 55 this manner, several notch-filers may act on several plates on the track simultaneously.

All movements and the application of the welding current are timed by the timer 49.

In another form of the invention, the alloy or 60 solder may be maintained in the molten state and a small quantity injected into the code notch, as shown in Figures 11, 12, and 13.

A section of the track assumes the shape of a die or mold 70. The notch marginal portion 13 65 of the plate 11 is tightly received longitudinally in a lateral undercut groove 71 in one side of the track. The plates may be fed longitudinal of the track, as in Figure 1, or the outer side of the track may be hinged to the bed piece 72 of the track, 70 as at 73 to permit lateral feed. A small aperture 74 is provided in the inner side, communicating between the groove 71 and the exterior for the injection of molten alloy into the code notch 10, when the latter is located opposite the aperture.

A melting pot 75 contains molten solder or alloy

76 maintained at a suitable temperature by a jacket of heating medium 78. Within the pot a vertical pump tube or barrel 79 is provided with an inlet port 80, intermediate of its lower fixed and closed end and its upper open end. A vertically reciprocatory piston 81 is tightly disposed in the tube 79 and adapted to be operated by a lever 82, pivoted to an extension 84 of the pot. Intermediate of the inlet port 80 and the closed end of the tube 83, an outlet port 85 is provided for the ejection of the alloy. A tube 86, having a bore preferably of small or capillary size, has its respective ends fitted into the outlet port 85 of the pump tube 79 and into the die aperture 74 of the die or mold 70, to connect the pump to the mold.

In operation when the piston is above the port 80, alloy may flow into the lower part of the pump tube, but will not flow through the capillary tube 86. As the piston descends, the port 80 is closed by the piston and the alloy forced through the capillary tube and into the mold 70, so as to fill the core notch 10. A plurality of pumps may be used to fill a plurality of notches.

Jacketing means may be provided to prevent the alloy from solidifying in the capillary tube or mold, such as pipe 88 associated with passages 89 in the mold.

It is obvious that slight changes may be made in the form, construction and arrangement of the several parts, as shown, within the scope of the appended claims, without departing from the spirit of my invention, and I do not, therefore, wish to limit myself to the exact construction and arrangement shown and described herein.

Having thus described my invention, what I claim as new and desire to secure by Letters Patent of the United States is:

1. A method for filling notches in plate material with wire alloy, having a lobe on one end thereof, said method comprising holding the material, feeding the wire in line with the notch and parallel to the axis thereof, past the material, so that the lobe clears the notch, forcing the wire laterally into the notch and cutting off the lobed end of the wire substantially flush with a face of the material, melting the wire in the notch and off from the remainder of the wire stock, and smoothing the molten alloy in the notch, so as to be substantially even with the opposite face of the plate material.

2. A device for filling notches in flat plate material with wire alloy, having a lobe on one end thereof, said device comprising means for holding the material, means for feeding the wire in line with the notch and parallel to the axis thereof, past the material, so that the lobe clears the notch, and an electrode reciprocatorily mounted to move substantially in the plane of the plate material and having an end portion with an upper surface in the plane of one face of the material and adapted to slide under the material and provided with a bottom for the notch, the electrode having a wall substantially at right angles to said surface and engageable with the edge of the plate material, to close the lateral opening of the notch.

3. A device for filling notches in plate material with wire alloy, having a lobe on one end thereof, said device comprising means for holding the material, means for feeding the wire in line with the notch and parallel to the axis thereof, past the material, so that the lobe clears the notch, means for forcing the wire laterally into the notch and cutting off the lobed end of the wire substantially flush with a face of the ma-

terial; means for melting the wire in the notch and off from the remainder of the wire stock, and means for smoothing the molten alloy in the notch, so as to be substantially even with the opposite face of the material.

4. In combination, means for holding a printing plate, having a lateral notch in the lateral marginal portion thereof, means for feeding a rod or wire of alloy, almost in the notch and substantially perpendicular to and across the plate, an electrode adapted to reciprocate substantially in the plane of the plate and lateral thereto; said electrode having an L-shaped end portion directed toward the notch, providing a

15 recess to receive the marginal portion of the plate, the upper face of the base arm being adapted to engage the lower face of said plate and being provided with a cutting edge at the end thereof, whereby, when the wire is lying across the margin of the plate, the inward movement of the base arm will force the wire into the notch and cut the wire off, even with one face of the plate, and serve as a closure for one side of the notch, the vertical arm of the L-shaped portion

20 being at least as high as the thickness of said marginal portion, so that after the wire is forced into the notch, the vertical arm will cover the outer opening of the notch, and a source of current connected to said electrode and plate.

5. In combination, means for holding a horizontal printing plate, having a lateral notch in the lateral marginal portion thereof, means for downwardly feeding a rod or wire of alloy, in line with and near the notch, until the lower end of

35 the wire projects below the plate, an electrode adapted to reciprocate substantially in the plane of said plate and lateral thereto, the wire being fed between the notch and the electrode; said electrode having an L-shaped end portion di-

40 rected toward the notch, provided with a horizontal recess to receive the marginal portion of the plate, the inner faces of the arms being adapted to engage the outer and lower faces of the plate, the base arm of the L-shaped portion being longer than the depth of the notch and provided with a cutting edge at the end thereof, whereby, when the wire is positioned across the margin of the plate, the inward movement of the base arm will force the wire into the notch and cut the wire off even with the lower face of the plate and serve as a bottom closure for said notch;

45 the upper arm of the L-shaped portion being about as high as the thickness of the plate, so that after the wire is forced into the notch, said upper arm will force molten alloy laterally into the notch and fill any voids and form a smooth edge surface, and a source of current connected to said electrode and plate, substantially as shown and described.

6. In combination, means for holding a printing plate having a lateral notch in the lateral marginal portion thereof, means for laying a rod or wire of alloy adjacent the notch and substantially perpendicular to and across the plate, an electrode adapted to reciprocate substantially in the plane of the plate and lateral thereto, said electrode having an L-shaped end portion di-

65 rected toward the notch provided with a recess to receive the marginal portion of the plate, one of the arms of the L-shaped portion being longer than the depth of the notch and provided with a cutting edge at the end thereof, whereby, when the wire is lying across the margin of the plate, an inward movement of the arm will force the wire into the notch and cut the wire off even with

one side of the plate and serve as a closure for one side of the notch, the other arm of the L-shaped portion being engageable with one of the faces of the marginal portions of the plate and adapted to cover another side of the notch and smooth the alloy in said notch, and a source of current connected to said electrode and plate.

7. In combination, means for holding a horizontal printing plate, having a lateral notch in the lateral marginal portion thereof, means for downwardly feeding a wire of alloy near and in line with the notch, until the wire projects below the plate, an electrode adapted to reciprocate substantially in the plane of the plate and lateral thereto, the wire being between the electrode and plate; said electrode having an end portion directed toward the notch provided with a smooth upper surface, adapted to engage the lower face of the plate, and a substantially vertical surface adapted to engage the lateral marginal portion, whereby when the wire is positioned across the margin of the plate, the in-

ward movement of the electrode end portion will force the wire into the notch and cut the wire off, even with one side of the plate and serve as a bottom closure for the notch, the vertical portion will mold the edge portions of the alloy, and a source of current connected to said electrode and plate.
